UNITED STATES PATENT OFFICE.

WILLIAM O. MEISSNER, OF CHICAGO, ILLINOIS, ASSIGNOR TO PETER C. BURNS, OF SAME PLACE.

ANNUNCIATOR FOR TELEPHONE-SWITCHBOARDS.

SPECIFICATION forming part of Letters Patent No. 624,838, dated May 9, 1899.

Application filed November 17, 1898. Serial No. 696,693. (No model.)

To all whom it may concern:

Be it known that I, WILLIAM O. MEISSNER, a citizen of the United States of America, and a resident of Chicago, Cook county, Illinois, have invented a certain new and useful Improvement in Annunciators for Telephone-Switchboards, of which the following is a specification.

At the central office of a telephone system a switchboard is provided, by means of which operators are enabled to establish connections between the various lines of the subscribers for the purpose of conversation. It is necessary at such switchboards to provide means whereby the attention of the operator may be directed to any line by any one or more of the subscribers. For this purpose what are termed "annunciators" are employed, located upon the switchboard, one or more for each subscriber's line. These annunciators are operated by a current of electricity generated by means of an electric machine at each subscriber's station.

My invention relates to certain improvements in the annunciators; and it consists in certain features of construction and details of arrangement to be described, and pointed out in my claim, reference being now had to the accompanying drawings, in which—

Figure 1 is a side elevation of my annunciator. Fig. 2 is a central longitudinal section. Fig. 3 is a plan view. Fig. 4 is a cross-section on the line 4 4 of Fig. 1. Fig. 5 is a rear view.

My invention relates to certain improvements in that class of annunciators of the tubular type which employ a magnetic sleeve enclosing the electromagnet. In these so-called "tubular drops" the electromagnet operates an armature pivoted or hinged in the rear of the electromagnet and at the upper side thereof, which extends from the rear to the front of the magnet and terminates in a latch, which is adapted to normally engage and hold a pivoted shutter located in front of the magnet. When a current of electricity is sent from a subscriber's station, it traverses the coils of the electromagnet of the annunciator of such subscriber on the switchboard, which magnet then attracts the armature and releases the shutter, which then falls, thereby giving a

visual signal to the operator that this subscriber desires connection with some other line. As my invention relates only to improvements in this signal device, it is unnecessary to describe the further operations for connecting the two subscribers together. 55

The object of my invention is to provide a drop or annunciator which shall be more sensitive in operation, and therefore require a 60 current of less strength to energize the electromagnet and move the latching-armature to release the shutter, and also to provide means whereby access may be readily had to the electromagnet and its connections for repair and the like.

Having reference now to the drawings previously described, it will be observed that the electromagnet is designated at A, Fig. 2, disposed within the shell or sleeve B of magnetic 70 material.

The armature D is pivoted at D² to the curved supporting-arms E. The armature latch-arm H is secured to and extended from the upper portion of the armature D and at a point remote from the pivot D² of said armature. Said latch-arm H extends forward beyond the face-plate J and has formed therewith a latch H², adapted to engage and normally hold the shutter K in a vertical restored 80 position.

The face-plate J is secured to and held by the arms E, which latter are secured to the magnetic sleeve B.

A guard or protector L is provided, projected 85 from the face-plate J, just above the latch H², which serves to protect the normal engagement of the latch with the drop-shutter and prevent accidental disengagement.

On the rear of the electromagnetic sleeve 90 B ears a a are secured, and ears b b on the head M of the electromagnet A are adapted to coincide with the ears a a and afford means for fastening the electromagnet A within the sleeve B by screws through the joined ears 95 a a and b b. Access may be conveniently obtained to the electromagnet by withdrawing the screws from the ears and then pulling the electromagnet longitudinally out of the sleeve, as shown in Fig. 3 by the dotted lines. 100

An insulating-block N is also secured to the face-plate J and holds the night alarm-con-

tacts L². A circuit common to all of the drops or annunciators is connected in turn to each of these sets of night alarm-contacts and a common audible signal device is included in the circuit. The night alarm-circuit is normally open at the annunciators; but when the drop-shutter falls the contacts are operated by the shutter to close the circuit to the signal device, which gives an audible alarm and serves in the night-time, when the number of operators in attendance is reduced, to attract the attention of the operator.

It will be observed that the armature of the electromagnet is pivoted or hinged at its lower end or edge and is thereby held, so that it requires but little attractive influence or energy to move the armature, operate the short arm of the latch, and release the shutter. The necessary movements of the armature are also exceedingly minute and a sensitive responsive action obtained by a greatly-reduced current strength.

Having thus described my invention, what I claim as new therein, and desire to secure by Letters Patent, is—

In an annunciator for telephone-switchboards the combination of the following instrumentalities: a front plate or support, carrying a pivoted shutter, a pair of supporting-arms extending rearwardly from and attached to the front plate, a metal cylinder mounted on said arms, a detachable cover closing its rear end, an electromagnet in said cylinder, an armature between said cylinder and the front plate, said armature being pivoted at its lower extremity between the supporting-arms; a latch-arm extending forwardly from the upper extremity of said armature through the front plate to engage the shutter, and an insulating-block lying between the supporting-arms and carrying contact-springs to co-operate with the shutter, substantially as described.

Signed by me, at Chicago, Cook county, Illinois, this 8th day of November, 1898.

WILLIAM O. MEISSNER.
